(57) **CLAIM**

The ornamental design for a glove palm, as shown and described.

DESCRIPTION

FIG. 1 is an enlarged front view of the glove palm showing my new design.

FIG. 2 is a cross-sectional view taken at Line 2-2 of FIG. 1; FIG. 3 is a front perspective view of a glove with the glove palm of FIG. 1;

FIG. 4 is a front elevation view thereof;

FIG. 5 is a rear elevation view thereof;

FIG. 6 is a left side view thereof;

FIG. 7 is a right side view thereof;

FIG. 8 is a top plan view thereof; and,

FIG. 9 is a bottom plan view thereof.

The broken line showing of a glove is included for the purpose of illustrating portions of the “article” and forms no part of the claimed design.

1 Claim, 9 Drawing Sheets
